UNITED STATES PATENT OFFICE.

CHARLES W. BURGTORF, OF PETALUMA, CALIFORNIA.

CHAFE-PAD FOR HARNESS.

SPECIFICATION forming part of Letters Patent No. 286,260, dated October 9, 1883.

Application filed May 17, 1883. (No model.)

To all whom it may concern:

Be it known that I, CHARLES W. BURGTORF, of Petaluma, county of Sonoma, State of California, have invented an Improved Chafe-Pad for Harness; and I hereby declare the following to be a full, clear, and exact description thereof.

My invention relates to a new and useful pad for harness, the object of which is to prevent chafing on the side of the horse.

It consists in a flap of leather sewed into the bend or fold of the hame-tug just inside or back of the trace-buckle, and adapted to receive the back-band, whereby it is held flat, and said buckle is prevented from rubbing or chafing the side of the horse.

This invention is particularly adapted for double harness, as the trace-buckle is brought in closer proximity to the horse than in single harness.

Referring to the accompanying drawings, Figure 1 is a perspective view of my chafe-pad for harness, showing it in connection with surrounding parts. Fig. 2 is a rear view of same.

A is the hame-tug, having a keeper, *a*, and being attached at its rear end to a trace-buckle, B.

C is the trace or tug, engaging with the buckle B, and having its end inserted in the keeper *a* of the hame-tug. I have here shown a well-known form of trace-buckle, though any one usually used at this point in the harness would answer.

D is the belly-band, and E is the back-band, which are secured to the trace-buckle above and below, as is usual. These two bands bind the buckle against the side of the horse, which results in chafing and soreness.

F is my pad. This consists of a flap of leather wider than the trace-buckle, in order to intervene completely between said buckle and the horse's side. This flap has a slot, *f*, in its forward edge, by means of which it is secured in the bend or fold of the hame-tug A by reason of said tug passing through the slot. This pad has also a top slot, *g*, through which the back-band passes. This permits the pad to lie flat, and at the same time effectually secures it without the aid of metallic or other fastening devices. The intervention of the pad at this point prevents the trace-buckle from coming in contact with the side of the horse, and therefore avoids all liability to chafe. It is not in the way, and presents a neat appearance.

I do not wish to be understood as claiming, broadly, a chafe-pad arranged in harnesses where there are metal mountings, as I am aware it is not new; but,

Having thus described my invention, what I claim as new, and desire to secure by Letters Patent, is—

In a harness, the hame-tug A, trace-buckle B, and the back-band E and belly-band D, whereby the trace-buckle is drawn up close to the horse, in combination with the leather flap or pad F, having slot *f*, whereby it is secured in the fold of the hame-tug, and slot *g*, to receive the back-band, said flap or pad lying between the trace-buckle and the horse's side, substantially as and for the purpose herein described.

In witness whereof I hereunto set my hand,

CHARLES W. BURGTORF.
